UNITED STATES PATENT OFFICE.

JOHN W. MAGNESS, OF ST. LOUIS, MISSOURI, ASSIGNOR TO LEVY MAYBAUM, OF NEWARK, NEW JERSEY.

ADDING ATTACHMENT FOR TYPE-WRITERS.

SPECIFICATION forming part of Letters Patent No. 758,371, dated April 26, 1904.

Application filed August 22, 1901. Serial No. 72,924. (No model.)

To all whom it may concern:

Be it known that I, JOHN W. MAGNESS, a citizen of the United States, and a resident of the city of St. Louis, State of Missouri, have 5 invented certain new and useful Improvements in Adding Attachments for Type-writers, of which the following is a specification.

My invention relates to type-writers, and has for its principal object to provide a register therefor which will automatically add the various amounts tabulated in a vertical column and visibly indicate the aggregate of the amounts tabulated in such column.

My invention comprises an adding-machine 15 adapted to be actuated by the numeral-key levers of the type-writer. It also consists in the parts and in the arrangements and combinations of parts hereinafter described.

In the accompanying drawings, which form 20 part of this specification, and wherein like symbols refer to like parts wherever they occur, Figure 1 is a front view of a type-writer provided with my attachment. Fig. 2 is a vertical section of the adding device on the line 2 2 of Fig. 4 looking to the right. Fig. 2^a is a detail view showing the device for limiting the band-hooks. Fig. 3 is a vertical section of the adding device on the line 3 3 of Fig. 4 looking to the left. Fig. 4 is a front view 25 of the adding device. Fig. 5 is a detail view of the spring-detent mounted in one of the wheels of the adding device. Fig. 6 is an end elevation of the attachment and devices connected thereto. Fig. 7 is a detail view of the 30 devices for transmitting motion from the paper-carrier to the adding device. Fig. 7^a is a detail view showing the engagement of the detent-lever 42 with the toothed bar. Fig. 8 is a detail view showing the connection of the 35 numeral-key levers to the bar-lever which actuates the adding device. Fig. 9 is a fragmentary view on the line 9 9 of Fig. 7.

My adding device comprises a series of gear-wheels 1, loosely journaled upon a common 40 axle 2 and provided with suitable means whereby each wheel will drive the next succeeding wheel one-tenth of its circumference forward for every revolution of its own. Each gear-

wheel 1 carries a drum 3, upon the circumference of which are the figures "0" to "9." 50 Said wheels are inclosed within a casing 4, which has a horizontal opening or window 5 therein for reading the numbers in horizontal alinement on the several drums. The general construction and arrangements are similar to 55 those commonly used in registers.

In the construction shown in the accompanying drawings the axle 2, upon which the several gear-wheels 1 are journaled, is mounted on the frame 6 of the adding device, and 60 the adjacent wheels are separated from each other by thin plates or partitions 7, mounted on the framework or casing. Upon the side of each gear-wheel is an annular series of ratchet-teeth 8, and on the side of the next 65 adjacent drum is a bent pawl 9, pivoted in position to coöperate with said ratchet-teeth. Each partition 7 has a hole or slot 10 cut therethrough of proper size and in proper position to allow one end of the pawl of one 70 wheel to engage the circular ratchet of the next succeeding wheel or drum and to drive it one-tenth of a revolution. In order to cause said pawl to engage said ratchet, an opening 75 concentric with the shaft or axle is formed in said partition-plate, and the other end of the pawl is pressed through said opening by means of a spring. A portion of the edge of this opening is formed in a straight line or spiral curve, so as to constitute a cam 11, 80 against which said pawl bears and is turned on its pivot, so as to force the first-mentioned end of the pawl through the opening in the partition and into engagement with the corresponding ratchet-teeth. This-pawl-and 85 ratchet connection permits each wheel to be moved entirely independently of those on one side of it, but causes each wheel intermittently to turn the next adjacent wheel on the other side one step for each revolution of its own. 90

The motion of the gear-wheel is effected as follows: Each gear-wheel 1 meshes with one of a series of gear-wheels 12, journaled loosely on a shaft or axle 13, mounted in the frame of the adding device. Each of these gear-wheels 95 12 has a drum 14 separated therefrom. In-

side of each drum is a coil-spring 15, fastened at one end to the shaft 13 and at the other end to the drum 14, whereby said drum is automatically returned to its normal position by 5 said spring. Upon each drum or gear-wheel is a spring which coöperates with a pivotal 10 detent to form therewith a spring-pawl 16 in position to engage a ratchet-wheel 17, mounted on the corresponding drum 14. On the out- 15 side of each drum is fastened one end of a band 18, whose other end extends downwardly, through an opening provided therefor in a bottom or partition plate 19 and is equipped with a hook or lateral projection 20 at its end 20 and with a stop at said end to engage the bottom or partition plate. The retracting-springs 25 15 keep the bands normally wound, so that the hooks rest in horizontal alinement slightly below the bottom or partition plate. When one of said hooks 20 is pulled downwardly, it causes its drum 14 to turn, whereby the pawl 16 of said drum drives the corresponding gear-wheel 12, which in turn drives the gear-wheel 1 and figure-drum 3. When the pressure on 30 the hook 20 is released, the spring 15 retracts the drum 14 and band 18, the pawl 16 sliding back freely over the ratchet-teeth 17. The several hooks or lateral projections on the bands 16 are individually operated by a hook 35 21, mounted upon a bar 22, which slides in vertical guides 23, provided therefor on the type-writer frame 24. This last-mentioned hook 21 is in the same vertical plane as the series of hooks 20 on the bands; but it is at a 40 higher elevation, whereby with the movement of the adding device each band-hook 20 in turn is brought under the overlapping actuating-hook 21. The bar 22, upon which this actuating-hook 21 is mounted, is connected by a link 45 25 to a lever 26, which lever is mounted on the framework of the type-writer. Each of the numeral-key levers 27 of the type-writer has a separate link 28, which is fastened to a key-lever at one end and has a loop or hook 50 29 at its other end in position to overlap the bar-lever 26, whereby the downward movement of each numeral-key lever is transmitted to the bar-lever 26, while the bar-lever itself may move without producing any movement 55 of any of the key-levers. The connections of the key-levers to the bar-levers are made at such points that the angular movements transmitted to the hook-bar 22 will be multiples of the movement thereof caused by the key-lever 60 of the numeral "1." For this purpose it is obvious that the connections corresponding to the largest numeral will be closest to the fulcrum of the bar-lever, so as to cause a greater angular movement thereof for a definite length of cord.

In order to avoid having the bar-lever of undue length, it is preferable to arrange the loop 29 corresponding to the numeral "1," so

as to rest normally some distance above the bar-lever. By this arrangement the initial 65 downward movement of this loop is lost and only the latter portion of such movement is effective in actuating the bar-lever.

By the foregoing arrangement the depression of any of the numeral-key levers 27 causes the bar-hook 21 to be pulled downwardly a single unit of distance or some multiple of this unit, according to the particular numeral-key depressed. In order for this downward pull on the bar-hook to be effective on the adding device, the adding device must be in such position that said bar-hook overlaps one of the band-hooks 20 of the adding device, in which case the downward pull on the bar-hook will operate the particular 80 register-wheel connected to the overlapping band-hook. For this purpose the adding device is mounted on horizontal guides 30 on the type-writer frame and is pulled along said guides parallel with the paper-carrier 31 by 85 a coil-spring 32, mounted on the type-writer frame and connected to it by a cord or band 33. The movement of the adding device along its guides is made dependent upon that of the paper-carrier by the following arrangement: A short rack 34, having at its lower end a base adapted to straddle the front bar of the type-writer carriage, is adjustably mounted thereon. The bar is provided with a series of recesses 46. The boss 44 on the 90 base of the rack-bar has a perforation which may be brought into register with any one of the recesses 46. A pin 45 extends through the base 44 and into the perforation on the bar, and thus secures the rack 34 in any given 100 position of adjustment. The short rack 34 meshes with a gear-wheel 35 on a short shaft 36, fixed to the frame of the type-writer. A second gear-wheel 37 on this shaft meshes with a rack 38 on said adding device, whereby the movement of the paper-carrier is transmitted through said gears to the adding device. As shown in the drawings, the gear 37, meshing with the rack on the adding device, is considerably larger than that meshing with 110 the carrier-rack in order that the movement of the adding device may be greater than the short space traversed by the carrier, and thereby give room for the register mechanism. By this arrangement the adding device begins to move and space as soon as the rack on the frame of the paper-carrier engages the stationary gear-wheel, and as soon as said rack becomes disengaged the adding device is 115 retracted by its spring. Thus the point at which the series of band-hooks come into operative relation to the bar-hook, and therefore the location on the paper of the vertical column of figures to be added, are under the direct control of the operator.

In order to render the adding device inop-

erative, the bar 22 is so mounted as to be capable of sufficient transverse movement to carry its hook clear of the series of band-hooks. For this purpose the guides 23, in which the 5 bar 22 slides, is pivotally mounted and the end of the bell-crank lever 40 bears against said guide and serves as a cam for moving it.

In order to prevent the adding device being pulled by its actuating-spring when the carrier is temporarily lifted out of engagement with it, a rack or toothed bar 41 is mounted on the back of the frame of the adding device, and a detent-lever 42 is pivoted on the type-writer frame in position to engage said 15 rack. This detent-lever is connected by a link 43 to an actuating bell-crank lever 40 in position to be easily manipulated by the operator. In its normal position the detent 42 is clear of the rack; but when the lever 40 is 20 raised the detent engages the rack and prevents movement of the adding device.

Obviously my device admits of considerable modification without departing from my invention. For instance, any suitable adding 25 device may be substituted for that hereinbefore described. Any device constituting a shifting operative connection between the bar-lever and the bands may be substituted for the interlocking hooks, and the various connecting and locking devices may be modified considerably. I do not wish, therefore, to be restricted to the construction hereinbefore described.

What I claim is—

35 1. The combination with a type-writer, of a lever operatively connected to each of the numeral-key levers so as to be moved predetermined distances by them respectively, an adding device and means for transmitting motion 40 from said levers to said adding device, said means comprising a hook connected to said first-mentioned lever and a series of hooks for co-operating therewith successively, said series of hooks being connected to the respective numeral-wheels, substantially as described.

2. The combination with a type-writer, of a lever operatively connected to the numeral-key levers, a register, and intermediate devices for transmitting motion from said 50 levers to said register, said intermediate devices being arranged to be rendered inoperative and comprising band-hooks operatively connected to the numeral-wheels and adapted to co-operate successively with a hook adapted to be actuated by the numeral-key levers, substantially as described.

3. The combination with a type-writer, of a lever operatively connected to the numeral-key levers, a register comprising a series of 55 numeral-wheels, and intermediate devices for transmitting motion from said lever to said register, said intermediate devices comprising a series of hooks operatively connected to the respective numeral-wheels and a hook con-

nected to said lever and arranged to interlock normally with each of said series of hooks but being movable to clear them, substantially as described.

4. The combination with a type-writer, of a lever operatively connected to each of the numeral-key levers to be moved different distances by them respectively, a register having a series of numeral-wheels, and intermediate devices for transmitting motion from said lever to said register, said intermediate devices comprising a series of hooks operatively connected to the respective numeral-wheels and a hook connected to said lever and arranged to interlock with each of said series of hooks, successively, substantially as described.

5. The combination with a type-writer, of an adding device arranged to be actuated by the numeral-key levers of the type-writer, racks mounted upon the type-writer frame and upon the adding device respectively, and a shaft 85 fixed to the frame of the type-writer and carrying gear-wheels meshing with said racks, the rack on the type-writer frame being adjustable relatively thereto, substantially as described.

6. The combination with a type-writer, of an adding device arranged to be actuated by the numeral-key levers of the type-writer, racks mounted upon the type-writer frame and upon the adding device respectively, the rack upon 95 the type-writer frame being adjustable relatively thereto, and a shaft fixed to the frame of the type-writer and carrying gear-wheels meshing with said racks, the gear-wheel meshing with the rack on the adding device being 100 of larger size than the gear-wheel on the type-writer frame, substantially as described.

7. The combination with a type-writer, of an adding device arranged to be actuated by the numeral-key levers of the type-writer, racks 105 mounted upon the type-writer frame and upon the adding device respectively, the rack upon the type-writer frame being adjustable relatively thereto, and a shaft fixed to the frame of the type-writer and carrying gear-wheels 110 meshing with said racks and a spring for retracting said adding device, substantially as described.

8. The combination with a type-writer, of an adding device arranged to be actuated by the 115 numeral-key levers of the type-writer, the frame of the type-writer being provided with a detent adapted to co-operate with a rack on said adding device to prevent the accidental return of the adding device when the paper-carrier is lifted out of engagement therewith, substantially as described.

9. The combination with a type-writer, of a lever operatively connected to the numeral-key levers, a register comprising a series of 125 numeral-wheels, and intermediate devices for transmitting motion from said lever to said register, said intermediate devices comprising

a series of hooks operatively connected to the
respective numeral-wheels and a hook con-
nected to said lever and arranged to interlock
normally with each of said series of hooks
5 but being movable to clear them, and means
for moving the hook connecting said lever
out of the plane of the series of hooks so as

to render it inoperative, substantially as de-
scribed.

St. Louis, Missouri, August 15, 1901.
